UNITED STATES PATENT OFFICE.

JOSEPH HIGGINSON AND HUBERT ARUNDEL, OF STOCKPORT, ENGLAND, ASSIGNEES TO STEWART WARNER SPEEDOMETER CORPORATION, OF CHICAGO, ILLINOIS, A CORPORATION OF VIRGINIA.

LIQUID-FUEL-SUPPLY APPARATUS FOR INTERNAL-COMBUSTION ENGINES.

1,270,157.

Specification of Letters Patent. Patented June 18, 1918.

Application filed November 18, 1916. Serial No. 132,187.

To all whom it may concern:

Be it known that we, JOSEPH HIGGINSON and HUBERT ARUNDEL, subjects of the King of Great Britain and Ireland, and residents 5 of Sovereign Works, Stockport, in the county of Chester, England, have invented certain new and useful Improvements in Liquid-Fuel-Supply Apparatus for Internal-Combustion Engines, of which the following is a specification.

This invention relates to liquid fuel supply apparatus for internal combustion engines of the type in which, between the fuel tank and the carburetor, there is interposed 15 an intermediate vessel (hereinafter termed the apparatus) into which the fuel is drawn by suction from said tank and from which it falls by gravity to the carburetor.

When the aforesaid type of apparatus is 20 fitted to an engine supplied through a carburetor having a large throughway aperture, or when the engine to which it is fitted is working at full or nearly full throttle opening and the engine is not racing or 25 revolving at high speed, as for example when a motor vehicle driven by the engine is climbing an incline on a high gear, it has been found that the apparatus fails to 30 lift the fuel from the low level tank; it is then necessary, in order to prevent the engine stopping for want of fuel, to close the 35 throttle valve more or less whereby the suction in the apparatus is increased. Such procedure, however, renders the apparatus 40 unsuitable for general application upon motor vehicles and for many other services. This defect is generally attributed to the absence of sufficient vacuum or reduction of pressure in the engine induction pipe or 45 manifold at full throttle opening, to lift the fuel from the low level tank.

By investigation and experiment, we have found that while there are continuous variations of pressure in the engine induction 50 pipe or manifold, due to the suction action of the pistons, the closing of the various inlet valves, and the checks to the flow of the fuel charge, yet the intensity of the vacuum

or reduced pressure which is produced when any one piston is moving at its maximum 50 velocity on its suction stroke is sufficient, and the duration of the periods of maximum vacuum (though short) is sufficiently long to work the apparatus and lift the fuel, if effective utilization thereof can be obtained. 55 We have further found that the said periods of maximum vacuum can be sufficiently isolated from the periods of reduced vacuum, though the change from the one condition to the other may be gradual but often re- 60 curring in a short period of time, and without in any material way throttling the suction action by impeding the transmission of the pressure reduction to the apparatus, by the fitting, within the suction connection 65 of the apparatus, of a disk (acting as a flap valve) of such thinness as to be of practically negligible weight, having its opening movement, due to the suction action, restricted to an exceedingly small amount, 70 while the valve aperture may be of relatively large area. We find that with this arrangement, we are enabled to lift the fuel through very considerable vertical distances 75 under the most disadvantageous conditions as regards pressure reduction in the engine intake or manifold, and thus render possible the use of the apparatus in many instances where heretofore it has failed or been considered impracticable. 80

Our invention therefore consists in the employment in the suction connection of the apparatus aforesaid, of a disk as before specified, serving as a flap or non-return valve and opening under the suction action. 85

Referring to the accompanying sheet of explanatory drawings:—

Figure 1 is a sectional elevation of an apparatus having our improved means fitted thereto.

Fig. 2 is a sectional elevation of the valve fitting.

Fig. 3 is a plan view of the valve and Fig. 4 a sectional elevation of the valve seating portion with the screws for limiting the 95 opening movement of the valve removed.

The same reference letters in the different views indicate the same parts.

The apparatus shown consists of a vessel comprising two chambers or compartments, 5 *b* and *c*, partitioned from each other by the chamber, *b*, being suspended within the chamber, *c*. Said vessel is disposed in the pipe line between the main fuel tank and the carburetor, the fuel being received from the 10 main tank (not shown) by the pipe *a* into the chamber *b* discharged thence into the chamber, *c*, through the communicating passage, *s*, whose discharge into the chamber, *c*, is controlled by a non-return valve, *t*. The 15 fuel is delivered from the chamber *c* by way of the connection *d* to the carburetor. The pipe *e* leads to the intake manifold of the engine which is the source of suction. The pipe *f* is for admitting air to the two chambers *b* and *c* for insuring a gravity feed to the carburetor. The float *g* in the chamber *b* acts to operate the suction control valve *h* and the air control valve *i* through toggle 20 lever or trip valve mechanism consisting of arms *j* and *k* loosely mounted on a pivot pin *m* and a spring or springs *n* acting on the ends of said arms so as to operate them with a trigger-like action when the spring or 25 springs has or have passed over the mid or neutral position. The float *g* may also operate a valve *o* upon the fuel inlet pipe of the chamber *b*. The said valve *o* is mounted on the arm *j* so that it is operated simultaneously with the valves *h* and *i*. 30

35 The vacuum or suction connection *e* with the valve *h* thereon is provided with our disk type valve consisting of the disk *p* which has its movement restricted by the heads of three screws *q*. The disk may be made of 40 steel, brass or other material. It is exceedingly thin, being for example, when made of steel, one two-hundred-and-fiftieth part of an inch thick and has an exceedingly small movement, as for example, one one-hundred-and-twenty-fifth part of an inch, the valve 45 throughway aperture being say one-fourth of an inch diameter.

Having now described our invention, what we claim as new and desire to secure by 50 Letters Patent is:—

1. In liquid fuel supply means of internal combustion engines, in combination, an intermediate vessel, a suction connection between said vessel and the engine inlet branch, 55 a fuel inlet to the vessel, an air inlet to the vessel, a valve upon said suction connection, a float within said vessel in operative connection with said valve, an automatic disk valve of practically negligible weight in said 60 suction connection, and means restricting the opening movement of said disk under the suction action to an exceedingly small amount, as set forth.

2. In liquid fuel supply means of internal combustion engines, in combination, an intermediate vessel, a suction connection between said vessel and the engine inlet branch, a fuel inlet to the vessel, an air inlet to the vessel, a valve upon said air inlet, a valve upon the suction connection, a float within 65 said vessel in operative connection with said valves, an automatic disk valve of practically negligible weight in said suction connection, and means restricting the opening movement of said disk under the suction action to an exceedingly small amount, as set forth.

3. In liquid fuel supply means of internal combustion engines, in combination, an intermediate vessel, a suction connection 80 between said vessel and the engine inlet branch, a valve upon said suction connection, a fuel inlet to the vessel, a valve upon said fuel inlet, an air inlet to the vessel, a valve upon said air inlet, a float within said vessel 85 in operative connection with said valves, an automatic disk valve of practically negligible weight in said suction connection, and means restricting the opening movement of said disk under the suction action to an exceed- 90 ingly small amount, as set forth.

4. In liquid fuel supply means of internal combustion engines, in combination, a compartmentally divided intermediate vessel, a communicating passage between the compartments, a non-return valve upon said passage, a suction connection between the upper compartment of said vessel and the engine inlet branch, a valve upon said suction connection, an air inlet to the upper compartment, a valve upon said air inlet, a float in said upper compartment in operative connection with said valves, an air inlet to the lower compartment, a fuel inlet to the upper compartment, an automatic disk valve of 95 practically negligible weight in said suction connection, and means restricting the opening movement of said disk valve under the suction action to an exceedingly small amount, as set forth.

5. In liquid fuel supply means of internal combustion engines, in combination, a compartmentally divided intermediate vessel, a communicating passage between the compartments, a non-return valve upon said 115 passage, a suction connection between the upper compartment of said vessel and the engine inlet branch, a valve upon said suction connection, an air inlet to the upper compartment, a valve upon said air inlet, a float in said upper compartment in operative connection with said valves, an air inlet to the lower compartment, a fuel inlet to the upper compartment, an automatic disk valve of 120 practically negligible weight in said suction connection, and screws in the disk valve 125

seat having their heads forming distance pieces for restricting the opening movement of said disk valve to an exceedingly small but adjustable amount, as set forth.

5. 6. In a construction such as defined in claim 1, a suction outlet port from the vessel being of very large diameter relatively to the movement of the disk valve which controls said port.

In testimony whereof we have signed our **10** names to this specification in the presence of two subscribing witnesses.

JOSEPH HIGGINSON.
HUBERT ARUNDEL.
